UNITED STATES PATENT OFFICE.

MARTIN H. CRANE AND SAML. A. TRAUGH, OF CINCINNATI, OHIO, ASSIGNEES
TO CRANE, BREED & CO.

DESIGN FOR A BURIAL-CASE.

Specification forming part of Design No. 2,228, dated December 12, 1865.

To all whom it may concern:

Be it known that we, MARTIN H. CRANE and SAMUEL A. TRAUGH, both of Cincinnati, Hamilton county, Ohio, have invented or produced a new and original Design for a Metallic Burial Case, Casket, or Coffin; and we do hereby declare that the following is a full and exact description of the same, reference being had to the accompanying drawing and photograph, making a part of this specification, in which—

Figure 1 is a transverse section at $x x$, Fig. 2. Fig. 2 is a perspective view of the case with the face-cover detached.

We claim and desire to secure by Letters Patent—

The design for a burial-case herein represented and described.

In testimony of which invention we hereunto set our hands.

M. H. CRANE,
S. A. TRAUGH.
